[57] CLAIM

The ornamental design for an artificial fingernail tip selector guide and display, substantially as shown and described.

DESCRIPTION

FIG. 1 is a top plan view of an artificial fingernail tip selector guide and display showing our new design; FIG. 2 is a side elevational view thereof looking from the left side of FIG. 1;

FIG. 3 is a side elevational view thereof looking from the right side of FIG. 1;

FIG. 4 is a side elevational view thereof looking from the lower side of FIG. 1;

FIG. 5 is a bottom plan view thereof; and

FIG. 6 is a side elevational view thereof looking from the upper side of FIG. 1.

FIG. 1

FIG. 2

FIG. 3

FIG. 4
